UNITED STATES PATENT OFFICE.

CLAUS J. WERNER CLASEN, OF DAVENPORT, IOWA, ASSIGNOR TO THE BETTENDORF COMPANY, OF BETTENDORF, IOWA, A CORPORATION OF IOWA.

CAR-TRUCK.

1,070,325.

Specification of Letters Patent.

Patented Aug. 12, 1913.

Application filed May 8, 1913. Serial No. 766,278.

To all whom it may concern:

Be it known that I, CLAUS J. WERNER CLASEN, a citizen of the United States of America, and resident of Davenport, Iowa, have invented a certain new and useful Improvement in Car-Trucks, of which the following is a specification.

My invention relates to improvements in trucks for railway cars and especially to that type of trucks in which the side frames including the top and bottom arch bars, columns and journal boxes are made of a single integral piece, and is directed more particularly to the manner of connecting the bolster to the truck frames with the view of greatly increasing the carrying capacity of the truck as a whole, without materially increasing the size or weight of its component parts.

0 The primary object of my invention is to provide means whereby the superimposed load is carried by the truck frames at points widely separated and at a distance from the center thereof, where it is usually carried.

5 Another object is to dispense with the usual "spring plank" and provide a truck wherein its component parts are held in proper and operative relation without the use of bolts or rivets.

) There are other objects which as will herein-after appear are attained by the structure illustrated in the accompanying drawings, in which—Figure 1 is a perspective view of the truck, less the wheels and axles, with my improvements in place. Fig. 2. is a front elevation of a preferred form of my improved truck side frame. Fig. 3. is a plan view thereof. Fig. 4. is a plan view of the truck bolster. Fig. 5. is a side elevation thereof. Figs. 6 and 7, 8 and 9 are side and end views of detail parts. Fig. 10 is a perspective view of the truck showing my invention in a modified form.

Similar numerals refer to similar parts throughout the several views.

In the drawings 1 indicates the side frames which are preferably made of cast steel and provided with integral journal boxes 2 and columns 3. These columns together with the top and bottom members of the side frame form the rectangular bolster opening 3^a for the reception of the ends of the bolster 4 which is also preferably made of cast steel and provided with the usual

center bearing 4^a and side bearings 4^b. The 55 bolster is also provided with the rectangular transverse slots 5 near each end. The upper wall of these slots being rounded or convex as shown at 5^a. These slots are engaged by the bolster carriers or slings 6 and 6^a which 60 pass through them, their upper edge being struck on a circle coinciding with the convex surface 5^a forming a bearing. These slings are four in number, two at each end of the bolster, one passing through the bolster 65 forward of the side frame one aft thereof.

Formed integral with the lower arch bar of the side frame, at a distance from each side of the bolster opening are the spring pockets 7, in which are located the bolster 70 springs 8. Fitted over the upper end of the springs are the spring caps 9 provided with the laterally extending trunnions 10 forming supports for and engaging the outer ends of the bolster slings 6 and 6^a. The 75 trunnions 10 may be made integral with the spring cap 9 or a removable pin may be used.

As is clearly shown in the drawings the bolster is passed through the bolster opening in the side frames and when in proper position its ends extend sufficiently beyond each side frame to bring one of the slots 5 at each end, forward of the side frame and the other to the rear thereof, so that when 80 the bolster slings 6 and 6^a are passed through the openings 5 and hung on the trunnion 10, they closely embrace the front and rear sides of the truck side frames locking the bolster against longitudinal movement, there performing the function of the usual bolster guide lugs and making unnecessary the use of the usual spring plank. Hanging the bolster in this manner on the 85 bolster slings, the entire weight of the 90 superimposed load is transferred from the center of the truck frames (where it usually 95 is carried) to points widely separated and near the axles. The maximum carrying capacity of a truck frame is thus greatly 100 increased without materially and proportionately increasing the size of the parts.

The present maximum carrying capacity of freight car trucks is 50 tons. To meet the growing demand for 60 and 70 ton 105 trucks, the common practice would be that of simply increasing the size of the parts and consequently the size of the truck gen-

- erally, in doing which, however, the M. C. B. regulations regarding center plate height and coupler height would be violated. Therefore to preserve the M. C. B. requirements and yet use springs of 70 ton capacity (which must be much larger and heavier than the former 50 ton springs) and not approach the rails closer with the lower side of the truck frame, nor the car body with the upper side, the novelty and utility of my method of transferring the load to points distant from the center of the truck frame becomes apparent. By locating the springs in the special spring pockets near the axles a much larger and heavier spring can be used. It would be impossible to use the same size spring under the bolster at the center of the truck frame without greatly increasing the height and size of the frame.
- 20 Fig. 10 shows a modified form of construction, in which, instead of passing the bolster slings or carriers through the bolster they may be made to pass under it as shown at 12. When constructed in this manner stop lugs 13 and 13^a would be provided on the underside of the bolster, engaging the outer surface of the slings or carriers thus locking the bolster against longitudinal movement.
- 25 It is to be understood that side frames with removable journal boxes as well as integral boxes could be employed without departing from the spirit of my invention.
- What I claim as new is—
- 30 1. In a car truck, the combination with side frames, each having a bolster opening mediate the ends thereof; a bolster the ends of which extend through said openings; bolster springs seated in said side frames on each side of said opening; bolster carrying members supported by said springs and directly engaging said bolster and adapted to form the sole support of the bolster and its superimposed load in said openings.
- 35 2. In a car truck, the combination with side frames, each having a bolster opening mediate the ends thereof; a bolster, the ends of which extend through said openings; bolster springs seated in said side frames on each side of said openings; combined, sole load carrying and bolster controlling members supported by said springs and directly engaging the ends of said bolster.
- 40 3. In a car truck, the combination with side frames, each having a bolster opening mediate their ends, a bolster extending through said openings, and means yieldingly supported by the side frame at points dis-

tant from said opening adapted to lock said side frames in operative position. 60

4. In a car truck, the combination with side frames, each having journal boxes at the ends thereof; a bolster opening mediate said journal boxes; load carrying springs applied to the said side frames at each side 65 of said opening; bolster supporting and guiding bars directly engaging the bolster and resting on said load carrying springs; a bolster, the ends of which pass through said bolster openings, said supporting bars 70 in conjunction with said bolster adapted to lock said side frames in operative relation.

5. In a car truck, the combination with side frames each having journal boxes at the ends thereof; a bolster opening mediate 75 said journal boxes; a pair of load carrying springs on each side of said opening arranged longitudinally of the side frame in the plane of the web thereof; springs caps on said springs provided with laterally extending trunnions; pairs of bolster supporting and guiding bars supported at their ends by said trunnions and on both sides of said side frames; a bolster guided by and locked in operative relation to the side frames by 80 said bars.

6. In a car truck, the combination with side frames each having a bolster opening therein; spring seats in said side frame on each side of said opening; springs on said 90 spring seats, a bolster, the ends of which extend through and beyond said openings; pairs of bolster carriers supported by said springs and directly engaging the ends of 95 said bolster fore and aft the side frames. 95

7. In a car truck, the combination with side frames each having a bolster opening therein; a bolster, the ends of which pass through and beyond said opening, lateral slots through the ends of said bolster fore 100 and aft of the side frames and adjacent thereto; means passing through said slots adapted to suspend said bolster in said opening free of the side frames.

8. In a car truck, side frames, interlocking means for said side frames consisting of a bolster the ends of which pass through the side frames and yieldingly supported carrier bars engaging said bolster fore and aft of said side frames. 105

Signed by me at Davenport, Iowa, this 5th day of May, 1913.

CLAUS J. WERNER CLASEN.
